UNITED STATES PATENT OFFICE.

JOSEPH K. LEEDY, OF HIGHSPIRE, PENNSYLVANIA.

MAIL-BAG-RECEIVING APPARATUS.

1,178,082.

Specification of Letters Patent.

Patented Apr. 4, 1916.

Application filed May 9, 1914. Serial No. 837,528.

To all whom it may concern:

Be it known, that I, JOSEPH K. LEEDY, a citizen of the United States, residing at Highspire, in the county of Dauphin and State of Pennsylvania, have invented certain new and useful Improvements in Mail-Bag-Receiving Apparatus, of which the following is a specification.

My invention relates to means for transferring mail from a moving train to a stationary support or vice versa.

As its primary object, the invention contemplates an improved and simplified receiving apparatus, such in its nature as to be tripped or operated by contact of the mail matter acted upon therewith.

The invention as a further object aims to provide a yieldable contact plate or abutment, so supported and mounted as to positively yet releasably retain the mail matter after transfer.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a top plan view of the receiving apparatus illustrating the manner in which the mail matter acted upon is moved into engagement therewith, and Fig. 2 is an enlarged longitudinal sectional view of the trip mechanism.

Referring now to the drawings by numerals, 1 designates a mail car and 2 the door thereof, the latter having the support means for the mail matter acted upon arranged therein. Said support means, as illustrated herein, comprises a vertical rod or shaft 3, journaled at its respective ends within the door frame, the support proper, designated as an entirety by the numeral 5 being vertically adjustable upon the said rod, such adjustment being controlled through manipulation of a suitable thumb screw 6. The said support proper 5 includes a handle 7, a shank 8 and arms 9, the latter carrying resilient retaining fingers 10 between which rings 11 are at each end of the

mail bag or pouch designated 12, are arranged, such arrangement as is obvious upon reference to the drawings, effectually supporting the mail bag in a manner whereby the same may be forcibly released by contact with the receiving apparatus positioned in its path. Fastening elements 13 may be provided to lock the mail bag support inoperative when not in use.

The receiving apparatus, as is apparent upon reference to Fig. 1 is positioned directly in the path of movement of the mail matter acted upon, said apparatus, in its preferred embodiment comprising a supporting structure 14 to which is attached as at 15 an arm 16, the latter being curved at its free end as indicated at 17, the curved end in turn supporting a contact plate 18, also curved, which contact is normally maintained in spaced relation to the said arm 17 through the medium of springs 19 interposed therebetween. To limit movement of the said contact plate and to guide the same during a transfer operation, I provide retaining pins or bolts 20, the same being rigid at one end with the contact plate and passing through openings of the arm 17, the springs 19 embracing the pin in a manner obvious upon reference to Fig. 1 of the drawings. Centrally of the curved portion 17 of the arm, trip mechanism designated as an entirety by the numeral 21 is arranged, said mechanism including a hollow casing 22 through the bore of which a trip pin 23 extends, the said trip being enlarged at one end as at 24, the enlargement being normally held projected or in the path of the mail bag 12 by means of a spring 25 within the casing, said spring abutting at one end the casing wall and at the opposite end an annular flange 26 of the pin. The contact plate 18 is rigid with the casing 22, while the curved portion 17 of the arm 16 serves as a support for the casing, the latter being bodily movable with the said contact when the latter is engaged by the bag or pouch to be transferred.

A trigger arm 27 pivoted as at 28 to a movable retaining arm 29 is arranged, in the set position of the receiving apparatus, to overlap the casing 22 and maintain a suitable helical spring 29' expanded, the said spring being attached at one end to the arm 29 at the pivot point 28 and at its opposite end to an extension 30 of the arm 16. Said arm 29 being fulcrumed intermediate

its ends as at 31 to the arm 16, it is apparent that the same, when released by disengagement of the trigger 27 with the casing 22, will move in the path of a circle from its 5 fulcrum point 31 toward the contact 18, and, as the mail bag acted upon is in engagement with the said contact at the moment arm 29 is released, obviously the arm 29 will grasp the mail bag and retain the same between 10 the said contact and the said arm.

From the foregoing, taken in connection with the accompanying drawings it will be noted that the action of the mail bag upon the trip pin 23 will force trigger 27 out of 15 engagement with casing 22, permit spring 29' to move arm 29 from its fulcrum point 31 to in this manner grasp and retain the mail bag between the said arm and the contact 18; that the tension of spring 25 will 20 return trip pin 23, the moment the pressure upon enlargement 24 is relieved, to its normal extended position, and, as the said trigger 27 is previously disengaged from the 25 said casing, it is apparent that movement of arm 29 is unrestricted; and that by the provision of the springs 19 interposed between the contact 18 and the arm 16, the stress and strain incident to the contact of the mail bag with the plate is to a certain extent 30 relieved.

In reduction to practice, I have found that the form of my invention, illustrated in the drawings and referred to in the above description, as the preferred embodiment, is 35 the most efficient and practical; yet realizing that the conditions concurrent with the adoption of my device will necessarily vary, I desire to emphasize the fact that various minor changes in details of construction, 40 proportion and arrangement of parts may be resorted to, when required, without sacrificing any of the advantages of my invention, as defined in the appended claims.

Having thus fully described my invention, what I claim as new and desire to secure by Letters Patent, is:—

1. A mail bag receiving apparatus in-

cluding a suitable support, a curved rigid arm affixed to the support, an oppositely curved movable arm pivoted to the rigid arm, a trip device movable relatively to the rigid arm and carried thereby, a yieldable contact plate movable with the trip device, means to yieldably support the contact plate forwardly of the rigid arm, a spring affixed 55 to the support and to the movable arm, and a hook element pivoted to the movable arm and disposed for engagement with the trip device to normally hold the movable arm at an approximate right angle to the rigid arm 60 and the spring expanded, as and for the purpose set forth.

2. A mail bag receiving apparatus including a suitable support, an arm rigid with said support, a contact plate disposed in the path of the mail matter acted upon, means carried by said arm and engageable with said contact plate to support the latter in spaced relation thereto, trip mechanism rigid with said contact plate and carried 70 by said arm, a casing, a trip pin projecting forwardly of said contact plate, said pin being engageable with the mail matter acted upon, spring means within said casing and engaging said trip pin to normally maintain 75 the same extended, a movable arm fulcrumed intermediate its ends to said rigid arm, and a trigger pivoted to said movable arm, said trigger being engageable with said trip mechanism, said trigger being automatically 80 released by engagement of the mail matter with said trip pin, and spring means connected to said support and to said movable arm to swing the latter when released into engagement with the mail matter for holding the same against said contact plate, as 85 and for the purpose set forth.

In testimony whereof I affix my signature in presence of two witnesses.

JOSEPH K. LEEDY.
